UNITED STATES PATENT OFFICE

120,655

DESIGN FOR A TEXTILE FABRIC

Charles Shapiro, New York, N. Y.

Application September 9, 1939, Serial No. 87,103

Term of patent 3½ years

To all whom it may concern:

Be it known that I, Charles Shapiro, a citizen of the United States, residing in New York, New York, have invented a new, original, and ornamental Design for a Textile Fabric, of which the following is a specification, reference being had to the accompanying drawing forming a part hereof.

The figure is a plan view of a textile fabric showing my new design. The dot and dash lines on the drawing outline substantially a design unit, which is repeated in the relation wherein angle A corresponds to A' and B corresponds to B'.

I claim:

The ornamental design for a textile fabric, as shown and described.

CHARLES SHAPIRO.
